UNITED STATES PATENT OFFICE.

JOHN C. BECK, OF MILTON, INDIANA.

GRAVE-LINING.

1,310,820.

Specification of Letters Patent. Patented July 22, 1919.

Application filed July 15, 1918. Serial No. 244,881.

To all whom it may concern:

Be it known that I, JOHN C. BECK, a citizen of the United States, residing in the town of Milton, in the county of Wayne, 5 State of Indiana, have invented a new and useful Grave-Lining, of which the following is a full, clear, and comprehensive specification and exposition, the same being such as will enable others to make and use the same 10 with exactitude.

The object of my present invention, broadly speaking, is to provide means for decorating the interior of a grave and the rough-box located therein, in order to produce an artistic *ensemble* prior to, and during the placing of a casket in the box.

And a further object is to provide a construction for the purpose set forth which may be easily manufactured, transported, 15 and placed in position at a comparatively low price.

Other objects and special advantages of the invention will suggest themselves in the course of the following explanation.

25 Referring now to the drawings: Figure 1 is a plan view showing the invention in position. Fig. 2 is a longitudinal central section as taken through a grave and the box located therein, and showing my invention 30 in position with relation thereto. Fig. 3 is an enlarged detail, showing the back of a portion of the lining. Fig. 4 is an enlarged detail, partly in section, showing the manner of connecting the parts of the invention. Fig. 5 is an enlarged detail, partly in section, showing the lower section and one manner of its attachment. And Fig. 6 shows a slightly modified manner of attachment.

40 Similar indices denote like parts throughout the several views.

Referring now to the drawings in detail: Letter A denotes the earth in which the grave B is formed in the usual manner, the 45 surface of the earth being designated by the letter C. Letter D denotes a rough-box which rests on the bottom of the grave.

The upper or grave section may be formed in one piece extending around and covering 50 the four walls of the grave, and for convenience of description I will refer to it simply as the upper section, but in practice it may be divided into four parts, one covering each side and each end of the grave walls. Numeral 1 denotes the main portion which

forms the vertical lining or skirt of the upper section, and it is of single thickness.

Numeral 2 denotes the outer portion of the flange, and 3 the inner portion of the flange, the two parts 2 and 3 being really 60 one piece doubled upon itself at its upper or outer edge. Located between the members 2 and 3 is the fabric member 4, which is secured near its upper edge by the line of stitching 5, thereby securing the fabric 4 65 between the members 2 and 3, with the fabric adapted to hang down below said portions substantially as shown. Around the upper edge of the part 1 is formed a ruffle 6. The junction between the part 1 and the 70 ruffle 6 is gathered and stitched, by the stitching 7, to the parts 2 and 4, but said stitching does not engage the part 3.

Near the center of the part 1 is a line of gathered stitching 8 whereby that part of 75 the member 1 between the stitching 7 and 8 will be Shirred, and that below the stitching 8 will be plaited.

For the purpose of securing the device in place in the grave I provide a plurality of 80 staples, each comprising two shanks 9 and 10 of unequal length with relation to each other and connected at their upper ends by the body 11, each of the shanks 9 and 10 has a sharp pointed lower end as shown. 85

To hold the device in place the two prongs 9 and 10 are to be inserted through the parts 3 and 4 and then through the surface C into the ground A, thereby suspending the upper section against the walls of the 90 grave with the flange extending out horizontally forming a border around the grave, the same being at right-angles to that which hangs in the grave, from which it is evident that the staples will be concealed, being covered by the part 2. The upper section just described is intended to hang down around the box D. 95

Now the lower section is identical with the upper section, except that it is shorter, 100 as it extends from the upper edge to the bottom of the box D, extending around inside the box, and it comprises the outer flange member 2', the inner flange member 3', the fabric member 4', the main portion 105 1', the ruffle 6', and the stitching 7'.

The staples for the lower section are identical with the upper staples and they each comprise the shanks 9' and 10', and the body 11', and they are inserted through the parts 110

3' and 4', with the prongs or shanks 9' and 10' fitting over the edges of the box D as shown in Fig. 5, which manifestly will hold the lower section in position.

5 All parts of this invention, including the upper and the lower sections, are made of paper, except the fabric head-lining 4 and the staples, the head-lining 4 being made of some cheap material such as cheese-cloth, 10 and the paper portions are formed preferably of crape paper or its equivalent, which may be of any desired color or embellishment.

I desire that it be understood that there 15 are two distinct features embodied in the invention: An upper grave-section and a lower grave section; but still more important is the fabric head-lining 4 in combination with the main portions of paper, where- 20 by a maximum of strength is attained and, the desired shape is maintained.

In practice the ruffles 6 and 6' may be dispensed with and the upper edge of the part 1 may be stitched underneath the 25 flanges 2 and 2', as shown in Fig. 6.

Having now fully shown and described my invention, what I claim and desire to secure by Letters Patent of the United States, is—

30 1. A grave lining comprising a double flange portion adapted to lie flat upon the ground around a grave, a skirt portion hav-

ing a ruffle at its upper edge and secured to said flange portion, all of said parts being formed of paper, a fabric having its upper 35 edge secured between the members of the flange and projecting down below the attachment of the skirt portion, and means for secretly securing the lining in position, substantially as set forth. 40

2. A grave lining comprising a double flange portion adapted to lie flat upon the edge of a box located in a grave, a skirt portion having a ruffle at its upper edge and secured to said flange portion, all of said 45 portions being formed of paper, a fabric lining having its upper edge secured between the members of the flange portion and projecting down below the attachment of the skirt portion, and staples adapted to be 50 inserted through said fabric and the under member of the flange portion and to stride the edges of the box to retain the device in position to cover the inner wall of the box, all substantially as shown and de- 55 scribed.

In testimony whereof I have hereunto subscribed my name to this specification in the presence of two subscribing witnesses.

JOHN C. BECK.
